PANTS

Francois Bamberger, Paris, France, assignor to
Hauser S.A.R.L., Paris, France

Filed July 30, 1962, Ser. No. 71,080

Term of patent 7 years

(Cl. D3—17)

FIG. 1 is a front view of a pair of pants showing my new design;

FIG. 2 is a side view thereof;

FIG. 3 is a rear view; and

FIG. 4 is an enlarged fragmentary view of a portion of the waistband and pants shown in FIG. 1.

I claim:

The ornamental design for pants, as shown.
